UNITED STATES PATENT OFFICE.

WILLIAM E. BIRKET, OF PEORIA, ILLINOIS.

SOUND-REPRODUCING MACHINE.

Application filed September 29, 1924. Serial No. 740,631.

This invention pertains to improvements in sound reproducing machines.

The main object of the invention is to produce a structure in a machine of this class that will admit of reproducing sound from all of the records of a series of record discs in successive order and automatically terminate the action of the machine; that all of the records may be reproduced in successive order and repeated again and again or until the action is terminated manually; and that also the mechanism may be rendered inoperative when desired to reproduce any given record independently in the customary way.

Another object is to furnish means by which the needle-arm of a sound reproducing machine may be automatically stationed at the proper starting point on a record disc without the necessity of specially grooving the latter as has been done in the past when used on certain machines.

Still another object is to furnish mechanism by which the sound reproducing parts may be caused to automatically take up the proper position in the record groove of any one of a stack of record discs regardless of the diameter of the discs or the position they may occupy relatively.

In addition, certain advantages are present in the machine of my invention due to the structures employed, which structures will form the subject of the appended claims.

In the accompanying drawings forming part hereof.

Figure 1 is a plan of my improved sound reproducing machine.

Figure 2 is a side elevation of the same on line 2-2, Figure 1.

Figure 3 is a plan of parts shown in Figure 1 but produced on a much larger scale.

Figure 4 is an elevation of parts shown in Figure 3.

Figure 5 is an elevation of parts illustrated in Figure 3 produced substantially full size, and shown in part section on line 5-5, Figure 3.

Figure 6 is a vertical section of means for tilting a sound box and needle arm, taken on line 6-6, Fig. 3.

Figure 7 is a plan of certain mechanism employed in my reproducing machine produced full size on line 7-7, Figure 2.

Figure 8 is a side elevation of the same as seen beyond line 8-8, Figure 1.

Figure 9 is a plan of certain mechanism

shown in Figure 8 illustrated by themselves to make them more clearly understood.

Figures 10 and 11 are elevations of certain parts shown in Figure 9 with certain parts in section as seen on lines 10-10 and 11-11 respectively of the latter figure.

Figure 12 is an elevation, in part section, of certain parts used as driving connections on line 12-12, Figure 7.

Figures 13 and 14 are respectively a plan and an elevation in detail of parts of what is shown in Figure 12, the former on line 13-13, Figure 18 to follow, and 14 on line 14-14, Figure 13.

Figure 15 is an elevation of certain parts illustrated in Figure 5 together with other parts not shown in said figure.

Figure 16 is an elevation of parts shown in Figure 7 on line 16-16 of that figure.

Figure 17 is an elevation of parts as would be seen on line 17-17, Figure 7, one of said parts being shown in section.

Figure 18 is an elevation of parts shown in Figure 12 together with other portions to operate therewith, and

Figure 19 is an elevation of a controlling switch.

The body of the machine is indicated by the character 1 and may be of any desired type. Suitably journaled in its top is a shaft 2 whose extension outside the body is provided with a series of removable supports or "turntables" 3 spaced from one another, each to receive a record disc 4. The shaft may be driven from any suitable source of power such, for example, as one of the customary spring motors, or it may be an electric motor, one such being designated at 5 in the drawings, the same being operatively connected to the said shaft 2 in any approved fashion.

Mounted upon the top of the body 2 is a frame for carrying certain operating parts to be described. In this instance, said frame consists of two spaced plates 6 held in rigid relation by spacers 7, Figures 7 and 8. A shaft 8 is journaled in the plates to which rotation is imparted through a shaft 9 geared thereto in any desired manner, said shaft 9 receiving its motion from the shaft 2 through beveled gears 10 and 11, for example, Figure 2. In said figure the shaft 8 and the said plates are shown but none of the mechanism lying between the plates has been shown since produced clearly in other figures on a large scale.

An amplifying horn 2' is shown within the

body 1, there being a vertically disposed sound carrying tube 12 depending into it over which is slideable, vertically, a larger tube 13 upon whose upper end is carried a sound box 14 best shown in Figures 3 and 5. The said sound box has the usual diaphragm 15 and includes at its lower side a tubular extension 16 which depends into the upper open end of the tube 13, Figure 6, the said box being pivotally supported at 17 upon a rotating head 17' free to turn on said tube. A stud 18 depends from a cross-bar 19 at the otherwise open lower end of the extension 16 whose purpose will appear later.

15 The sound box carries an arm 20 extending some distance therefrom or a distance substantially equal to the measurement between the said box and the center of the shaft 2 for the record discs. A needle-rod 21 is journaled in said arm 20 and is connected to the diaphragm 15 in the conventional manner by an arm 15'. Said rod 21 is adapted to rock and carries a reproducing needle 22, it being understood at this time that the axis 25 of the pivot at 17 for the sound box lies at right angles to the arm 20 so that the latter with its rod 21 can be raised and lowered at the free end.

30 Since the shaft 2 carrying the discs 4 may be of any length, and may carry any number of discs, the tube 13 carrying the sound box 14 may be of a length which on being raised and lowered will accommodate itself to reproduce any one of the discs of the series.

35 To this end there is secured to the side of the tube a member 23, U-shaped in cross section, Figure 7, having an opening 24 extending vertically. One of the resulting edges at the opening has a continuous series of teeth 25 extending along it, while the opposite edge is provided alternately with a series of teeth 26 and spaces 27 as clearly shown in Figures 8 and 15. The top edge in the opening 24 is likewise furnished with teeth 28.

45 The shaft 8 carries a beveled pinion 29 and meshing therewith is a similar pinion 30 affixed to a shaft 31 extending toward the tube 13 and having a pinion 32 on its end lying within the opening 24 and adapted at times 50 to engage any of the described teeth of said member 23, but normally lying in one of the spaces 27. The shaft 31 is mounted in posts or bearings 33 affixed to and upstanding from a plate 34 which plate is shiftable in this 55 instance upon the lower of the two plates 6 described, turning about or with respect to the said shaft 8 as a center, see Figure 8, whereby in the swing of said plate the pinion 32 of said shaft 31 may be caused to engage 60 with either of the sets of teeth 25, 26 as will appear. A worm 35 is affixed to the shaft 31 and is adapted at times to engage a worm-wheel 36 affixed to a shaft 37, Figures 7 and 18, said shaft carrying a pinion 38 in mesh 65 with a gear 39 splined on a shaft 40, the lat-

ter being adapted to turn with respect to said gear as will also appear. Secured to said gear 39 is one half of a clutch arrangement which in this instance is a cup-like member 41 wherein is a series of arms 42, for example, as parts of a cover-plate 43 which, together with a pinion 44, is free to turn on said shaft, the latter being adapted in operation to at times shift through the described parts, there being a ball or roller 45 lodged in a recess 46 of each arm in clutch fashion quite well known. The length of the shaft 40 is substantially equal to that of the tube 13 and its upper end, Figures 3 and 5, carries a pinion 47 meshing with a segment gear 48 affixed to the head 17', before described, of the sound box 14, and the lower end is journaled in an arm 49 extending from the tube 13, Figures 2 and 8.

85 The pinion 44 meshes with a segment gear 49' mounted on an arbor 50 journaled in the plates 6, there being included a lever 51 provided with an extension 52 in position to be engaged by a cam 53 secured on a shaft 54. The latter carries at its lower end a gear 55, which is free thereon and is in engagement with and driven by a pinion 56 on the shaft 8 just beneath the bevel pinion 29, Figure 8.

90 Adjacent the tube 13 is a rock-shaft 57 journaled at its lower end in the described arm 49 and at its upper end in an arm 49' extending from the tube 13, in which, also, the mentioned shaft 40 is journaled. Said shaft 57 is provided at its upper end with a cam 58 affixed to it adapted to engage the head 59 of a push-pin 60 extending through the head 17', said pin having engagement with the described stem 18 of the sound box 14. Secured to and extending from the shaft 57 is a lever-arm 61 which extends in the general direction of the shaft 54, the same having an extension 62 adapted to receive contact of a cam 63 on the said shaft 54. In addition, the said lever-arm 61 has a lateral extension 64 which in one of the movements of said lever is adapted to engage an adjustable stop 65 in one of the bearings 33 supporting the shaft 31.

105 Affixed to the shaft 54 just above the gear 55 is a plate 66 having a slot 67 therein arranged concentrically to the axis of rotation of said plate and having pivoted therein a pawl 67' adapted by gravity, for example, to fall into engagement with any one of a series of teeth 68 on the gear 55 arranged about the axis of its rotation. Said plate and its shaft may be prevented having too free movement. At certain times the pawl 67' is maintained disengaged from the teeth 68 by means now to be described. That is to say, in the lower of the two plates 6, Figures 8, 9 and 10 an arcuate slot 69 is created as a guide for a pair of plates 70, one at each side of said plate 6, which are connected by pins 71 lying within the slot and serving as guiding means. Ex- 110

tending from the upper of the two plates 70 is an arm 72 to extend to and overlie part of the slot 67 of the plate 66 and serves when in that position to engage one end of the pawl 67' to hold it free of the teeth 68, it being observed, Figure 9, that the slot 69 lies in such position with respect to the pawl 67' that the latter will be exposed when the arm 72 moves in the course indicated in dotted lines as the pins 71 traverse the slot 69. A spring 73 secured at one end to a post 74, for example, beneath the plate 6, and bearing at its other end against the lower of the two plates 70, serves to maintain the arm 72 upon the pawl 67' until certain actions to be described herein occur. Pivoted on one of the pins 71 is a pawl 75, which by means of a suitable spring 76 is kept against a stop 77 of the upper plate 70. It is to be observed, now, that certain of the parts just described lie beneath the shaft 31. Further, it is to be made known that the worm 35 while directly connected to the said shaft 31 is slideable along it and includes a hub 35' at whose outer end is a series of spurs or fingers 35² normally rotating without result. In the operation of the machine, however, said spurs at times engage the free end of the pawl 75 shifting it and the plate 70 with its arm 72 bodily along the slot 69, guided by the pin 71, drawing the said arm 72, rigid therewith, away from and uncovering the pawl 67' of the plate 66 releasing said pawl. A forked lever 77' pivoted on a bracket 78 of the plate 34 releasing said pawl, serves, through the spring 78', attached thereto and to an extension 79 of said bracket 78, to elastically hold the spurs 35² normally away from said pawl 75. It will be clear that since the lever 77', fulcrumed between its ends, is actuated by the spring 78', Figure 9, the end of the lever bearing against the hub 35' will shift the latter to a position where the spurs will be clear of the pawl 75 as in Figure 7. It will also be clear from a study of Figure 10 that at such times as the hub may be moved so that the spurs approach and lie opposite the end of the pawl as in Figure 9 one of them during rotation will engage the end of such pawl and cause the shifting action described.

It has been intimated that the tube 13 must be raised and lowered in order that the reproducing needle and the sound box may be properly located with respect to any record disc. The pinion 32 of the shaft 31 is adapted to impart a full raising movement to the said tube by engaging the teeth 25, and to lower the same by engagement successively with each of the series of teeth 26 as will be explained presently. Now, that the tube 13 may be properly guided in a free working manner I prefer, as one way to gain this result, to slot the tube longitudinally at diametrically opposite sides, for example, as indicated at 80, Figures 7 and 8, and to mount on the plates 6 flanged rollers 80' to engage

therewith. This furnishes a very smooth and free working arrangement. The shaft 31 being mounted on the plate 34 is at times to be shifted in position to engage certain of the mentioned teeth of the member 23. 70 Therefore, as already stated, the said plate 34 moves about the shaft 8 as a center. The movement of the plate may be both automatic and manual. The automatic action will be understood in the description of the operation. 75 The manual operation is through two agencies one of which is a rock shaft 81, Figures 7 and 8, mounted in the plates 6. This shaft has a hand lever 82 within easy reach when operating the machine manually and has a lowermost lever-arm 83, Figure 7, adapted to engage an extension 85 of the plate 34 for shifting the same. It also has an upper arm 84 which engages one end of a lever 86 for another purpose pivoted between its ends at 87 80 on the under side of the upper plate 6. The other end of said lever extends toward and lies in the path of movement of a pin 53' of the previously mentioned cam 53. The second manual operation involves the use of the lever arm 84 and its engagement with said lever 86 which latter lies in a notch 88 of a spring-held latch 89 guided in a post 90, Figure 17, one end being adapted to enter any one of a series of openings 91 in the member 23 90 for supporting the tube 13 in any given position. A third manual operation is through the employment of a sliding pin 92, Figures 7 and 8, extending through a slot 93 in the lower plate 6 and a slot 94 in said plate 34. 95 The slot 94 is an irregular one in that there is a notch 95 included therewith in which the said pin 92 may lie, as in Figure 7, as one of its positions.

There is a further but more shallow notch 105 at 96 in which said pin may lie as will appear in the description of the operation. Controlling the pin 92 is a rod 97 fixed relatively to it, which as shown in Figure 2, extends to and is controlled by a slide 98 on the top of the body 1.

Slidable through the plate 6 back of one edge of the plate 34 is a pin 100 carrying a member 101 forming a limiting stop for the said plate. A spring 102 maintains downward pressure on the member holding it upon the lower plate 6 but permitting it to lift when and as the said pin is raised by contact therewith of a stud 103 projecting from the tube 13, Figure 8, in the upward limit of movement of said tube. Such lifting of the member 101 permits the plate 34 to pass beneath it, Figure 7, due to the pressure of a suitable spring 104 held against the plate 115 through a stud 105.

I provide a switch control for the motor 5 located upon a plate 106, Figures 2 and 19, suspended beneath the top of the body 1, for example, adjacent the tube 13, a part of which may be made to lie in the path of the 120 130

stud 103 just referred to. A slide 107 is slotted at 108 and screws 108' extending therethrough act to guide the slide in a horizontal direction. A current conducting member 109 is secured on the slide but insulated therefrom and adjacent it is a second member 110 pivoted on the slide spring-held in contact with the member 109. Between the two members is pivoted a trip 111 free to rise and fall and having a pin 112 adapted to engage the member 110 for separating it from the member 109, said trip at certain times being placed in the path of the stud 103 of the tube 13 in the travel of the latter. The slide 107 is adjustable by a rod 97', Figure 2, extending to the said slide 98 on the top of the body 1 and in its path of movement is an upstanding arm 110' having a stop 110², the whole being mounted on the plate 106, by means of which the members 109 and 110 may be separated in the manual adjustment of the said slide.

That is to say, ignoring the relation of the members 109—110 as shown in Figure 9, for the moment, and supposing these members to be in contact, for the sake of an understanding of the manual operation, then a movement of the slide 107 to the right will bring the angled portion of the member 110 into engagement with the stop 110² with the result that the said member 110 will be separated from the member 109 and moved to the position shown.

In order to provide for the proper position of engagement of the reproducing needle with a given record disc there is mounted on the body 1 a series of arms 113 all of which are pivoted at one end upon a post 114 upstanding from said body, Figures 1, 2 and 3. The other end of each of the arms is arranged to be placed in contact with the periphery of one of the discs or that opposite which it lies. Any suitable support for the arms may be provided such, for example, as a post 115 from which project rods 116, but one of which is shown, Figures 1 and 3, it being understood that one of the said rods 116 is provided for each said arm 113. Mounted in the rear of the sound box 14 is a standard upon which is guided in suitable manner a slide 118, there being one of these slides for each arm 113. Said slides 118 are frictionally held in any position placed by means of a spring actuated stud 119 carried by the standard and engaging the slide in a well known manner, and each slide is connected with one of the arms 113 by a rod or link 120 preferably adjustable for length. The free ends of the slides are downwardly beveled at 121 as clearly shown in Figure 4 and each terminates in an extension 122 bent to create a vertically disposed channel 123. Extending from the rear of the sound box is an arm 124 to which is pivoted a lever 125 having a roller 126 at its free end to bear upon any one of the beveled edges

of the slides. The method of operation of the structure just described is as follows: Since there are several different diameters of record discs now in use it is clear that a machine for reproducing them must have some means for placing the reproducing needle at a point where it will enter the starting end of the record groove without loss of time. It will be observed in Figure 3 that the needle arm is located at approximately the proper starting position on the record disc. Also, that the roller 126 is in line with the channel 123 of one of the slides 118 which in this instance is connected with the arm 113 shown in contact with the periphery of the disc shown in the figure last referred to. The roller has passed down the incline of the slide, entered the channel and passed through and below the same locating the needle properly at the start of the record groove, the needle arm being now free to move inwardly on the disc.

The relations of the leverages of the arms to the points of connection with the slides 118 is such that any given slide will have the proper position to adjust the needle arm to the disc-margin of any disc regardless of its diameter when the arm 113 of that slide is moved up in contact with the periphery of that disc. The lever 125 is pivoted in order that as the sound box moves upwardly the roller 126 thereof in contacting with the several slides will be permitted to pass by without damage to any of the parts by dragging over said slides.

The operation of the machine aside from the above will now be described: With the needle arm in the position shown in Figure 3, with the motor in operation driving the shaft 2 and the shaft 8, the mechanism standing in the relation shown in Figure 7, the shaft 8 will be rotating in the direction of the arrow of Figure 7 or counter-clockwise. This rotates the shaft 31 together with its worm 35 through the pinions 29 and 30 in a clockwise direction and in turn rotating the shaft 40 counter-clockwise through the pinion 38, gear 39 clutch members 41, 43, rotating the pinion 47 at the top of said shaft 40 and finally the segment gear 48 of the sound box but at a speed slower than the travel of the needle in the record groove, the pinion 32 of the said shaft 31 rotating freely, the while, in one of the spaces 27 of the toothed member 23, the latter being held suspended by the latch 89, Figure 17. During the action of the shaft 8 the pinion 56 thereon also rotates the freely rotatable gear 55, of the shaft 54, in mesh therewith. Now, the needle upon reaching the inner terminus of the record groove necessarily sets up a resistance to further progress by lodging against the inner wall of the groove with the result that the said worm-wheel 36, being thus retarded due to being geared to the sound box, causes the worm 35, in rotating with respect to it, to

back away toward the pawl 75, Figure 10, in opposition to the tension of the spring 78', Figure 9, placing one of its spurs 35² against the end thereof shifting it and the plates 70 together with the arm 72 to remove the latter from and to release the pawl 67' of the plate 66. The release of said pawl 67' to permit its engagement with the teeth 68 of the gear 55 thus connects the latter with the 10 shaft 54 that carries it. Rotation of that shaft at once swings the lever 61 by means of the cam 63, Figure 7, turning the shaft 57 and placing pressure upon the push-pin 60, Figure 6, to lift the needle arm free of the 15 disc by contact of said pin with the stem 18 of the sound box. This action of the lever 61 moves its extension 64 against the stop 65 of the bearing 33 on the plate 34 shifting the latter to disengage the worm 35 from the 20 worm-wheel 36, the cam 63 due to its extensive circular form maintaining such disengagement until the cycle of operations is complete. Following the lifting of the needle arm the cam 53, Figure 7, engages the lever 25 51 swinging it and its segment gear 49 causing the pinion 44 to be rotated in a reverse direction with the result that the needle arm is swung outwardly free of the disc-margin so that in a lowering movement thereof with 30 the tube 13 it will be entirely clear of the stack of discs. The cam 53 leaves the lever 51 at this time, the shaft 40 coming to a stop. But a continued rotation of the shaft 54 carries the pin 53', of said cam 53 against the end 35 of the lever 86, the outer or other end of the latter being in engagement with the latch 89 withdraws that member from the member 23 so that the tube 13 is free to descend. Since 40 the pinion 32 is in position to engage the teeth 26 of the said member 23 the descent is checked and the steady rotation of said pinion carries the tube down until the latch 89, having one of the openings 91 brought opposite it, enters that opening and again suspends 45 the tube with the needle arm in position to be carried upon the disc next below the one previously reproduced. At this time the pinion is again free to rotate without result since one of the spaces 27 of the member 50 23 has been positioned thereat. Now, in the descent of the tube 13 the roller 126 of the sound box has met the inclined edge of the slide 118 corresponding to the disc now to be engaged by the needle and the needle arm is 55 carried to playing position ready for a succeeding operation.

When the tube 13 has dropped to its lowest point or limit of travel the teeth 28 in the top of the opening 24 of the member 23 engage 60 the constantly rotating pinion 32 whereupon, the tube 13 being fixed as against lateral motion, the pinion must travel across the opening swinging the shaft 31 and the plate 34 until the said pinion engages the teeth 25 at 65 which time the member 101 which up to this

time has been resting upon the said plate 34, now, in the altered position of the latter drops behind it and thus acts to positively maintain engagement of the pinion with said teeth 25. The tube 13 is now elevated to its highest position or until the stud 103 on the same meets the pin 100 of the member 101 shifting the latter and permitting the plate to regain its normal position and release the pinion from said teeth 25. The natural descent of the tube upon being thus liberated is now checked and held by the latch 89 as before ready for further reproducing action and step-by-step descents. The latch is beveled at its lower edge as shown in order that the member 23 may ascend without interference therefrom, said latch "clicking" over the parts of the member 23 as said member travels past it.

The structure employed enables me to use the machine as an ordinary one as used manually, or it may operate continuously by reproducing an entire lot of records over and over again as long as the motor is permitted to operate, or it may be made to reproduce the lot of records but once and then terminate its action. By placing the pin 92 in the notch 96, Figure 7, which will shift the plate 34 outwardly sufficiently to maintain separation of the worm and worm wheel 35, 36, respectively, the shaft 40 will be free to turn in either direction, the needle arm, therefore, being free to be used manually in the usual way, the action of the motor merely rotating the record shaft 2.

To operate continuously the pin 92 takes substantially the position shown in Figure 7, the worm and worm wheel being in mesh and the operation is as has been described herein, at which time the stud 103 while having a fixed path of travel cannot engage the trip 111 of the switch since the slide has not been advanced sufficiently to cause the breaking of the electric circuit and the machine will continue to operate indefinitely. However, a slight advance of the said slide 107 will project the trip 111 into the path of the stud 103 so that as the tube rises to its full height said stud will lift the trip and thus pass by it. In its next movement of descent the stud will engage the trip and depress it, breaking the circuit, this latter action, of course, following the engagement of the latch 89 with the member 23. Upon withdrawing the trip manually the circuit will be closed and the machine placed in action. The machine may be checked in operation at any time, however, by drawing back the slide 107 to cause the member 110 of the switch to engage the stop 110² to separate the same from the member 109.

The tube may be manually raised or lowered when it is desired to play any given record of the series by withdrawing the latch 89 by means of the lever 82 and grasping a con-

venient handle 13' on said tube as the control member.

The clutch arrangement for the shaft 40 provides that the needle arm will always be 5 positively operated to carry it toward the disc center, should it be retarded from any cause, but at the same time the relation of the teeth of the several gears is such that while the arm is freely moving across the disc the 10 shaft 40 and pinions 47 merely "follows" it. In other words the travel of the needle is faster than the drive imparted to the shaft. But at the end of the needle-travel the segment gear 48 and the said pinion 47 are, in 15 consequence of the described action, ready to move the needle arm outwardly upon the latter having been lifted free of the disc.

For the sake of brevity in some of the 20 claims the term "support" will be employed to designate both the disc carrying shaft 2 and the tube 13. Also, in some of the claims the shaft 40 and its associated members will be designated as "gearing" and the shaft 54 and its parts as "second gearing."

25 I claim:

1. A machine of the class described including, in combination, a shaft for carrying a series of disc records, a sound box and its needle arm, a support for the sound box paralleling the shaft disposed a fixed distance therefrom, means to impart movement to the support, means to fix the support with reference to any one of the discs, and means operatively engaging the sound box adapted to 30 oscillate it and swing its needle arm across any one of said discs adjacent to which it may be stationed.

2. A machine of the class described, including, in combination, a rotating support for 40 carrying spaced record discs, means to rotate it, a sound box and its needle arm, a support paralleling the first named support a fixed distance therefrom, adapted to move bodily parallel to the latter, a sound box and 45 its needle arm mounted on said second support means to impart movement to the said second named support in either direction, means to fix the same with respect to the first named support in a position whereby the said 50 needle arm will lie adjacent one of the record discs, and means operatively engaging the sound box adapted to swing the needle arm in either direction across a record disc.

3. A machine of the class described including a series of rotatably mounted spaced record discs, a support adjacent the same, a sound box and its needle arm carried thereby, means to automatically move the support in a line substantially paralleling the axis of 60 rotation of the record discs, means to automatically fix the support in a given position, and means geared to the sound box to automatically move the needle arm inwardly over a disc toward the center thereof and for

carrying it away from said center to the periphery of the disc. 65

4. A machine of the class described including a series of rotatably mounted spaced record discs, a support adjacent the same, a sound box and its needle arm carried thereby, 70 means to automatically move the support in a continuous manner in a line substantially paralleling the axis of rotation of the record discs, means to automatically terminate such movement, means to automatically fix the support at the termination of said movement 75 at a position where the needle arm will take up a station opposite one of said discs, means to carry the needle arm upon the disc, and means to positively move said needle arm across the disc during the period of sound reproduction. 80

5. A sound reproducing machine including a series of spaced disc records, a driven shaft carrying the same, a support paralleling the 85 shaft, means to automatically move the support in an unbroken travel in one direction, means to automatically terminate such travel, means to automatically fix the support at the 90 termination of its travel, and means to automatically release the support, the last named means being adapted to move the support in the other direction. 95

6. A sound reproducing machine including a series of spaced disc records, a rotary shaft carrying them, a support adjacent to and paralleling the axis of disc rotation, a toothed rack on the support having opposed teeth, a pinion to engage the rack adapted to move the support in a continuous travel in one direction, means to selectively engage the pinion with the rack for moving the support in either 100 direction.

7. A sound reproducing machine including a rotatable shaft for carrying a plurality of 105 spaced record discs, a sound box and its needle arm, a support carrying the same guided in a line paralleling the shaft, means adapted to engage and move the support in one direction in an unremitting manner and also to engage and move it in a step-by-step manner in an opposite direction, means influenced by the needle arm in its travel over a record disc to cause either of such engagements, means to fix the support with respect 110 to one of the discs at the termination of one of such step-by-step movements, and means to operate the last named means to release 115 said support.

8. A sound reproducing machine including a rotatable shaft and a plurality of record carrying members mounted thereon, a sound box and its needle arm, a support carrying the latter, continuously rotating means to engage a part of the support adapted to move it in an unremitting manner in one direction 120 in a line paralleling the shaft, and likewise adapted to engage another part thereof for 125

- imparting a step-by-step movement to the support in the other direction, means influenced by the needle arm to cause engagement of the first named means with one of 5 said parts, means to automatically fix the support with respect to one of the record members intermediate two of the step-by-step movements, and means to operate the last named means to release the support.
- 10 9. A sound reproducing machine including in its construction, together with a plurality of record discs, rotatable means carrying them, a sound box and needle arm, a support for said sound box, means to guide it in a line paralleling the axis of rotation of said discs, operating means to engage and automatically and positively advance the support in its guide in either of two directions to a given station, means to terminate the advancing movement at a station, and means in constant and positive engagement with the operating means and the needle arm for positively advancing the latter upon a disc at a rate of travel substantially equal to that of the advancement of the needle in its groove during the sound reproducing period.
- 15 10. A sound reproducing machine including in its construction, together with a plurality of rotatable record discs, a sound box and needle arm, a support for said sound box, means to guide it in a line paralleling the axis of rotation of said discs, operating means to automatically engage and advance the support in its guide in either of two directions to a given station, means to terminate the advancing movement means to positively engage and control the needle arm for positively advancing it entirely across the record disc during the reproduction period through 30 said operating means, and means influenced by the needle arm and cooperating with the last named means and said operating means to lift the needle arm and swing it clear of the disc.
- 40 45 11. A sound reproducing machine including, in combination, a series of sound record discs rotatable on a common axis, a sound box and its needle arm, a support movable in a line paralleling the axis of rotation of the discs and supporting the sound box thereon, operating means to automatically engage the support adapted for imparting movement to it in either of two directions, means to disengage the said operating means from the 50 support at any predetermined position of the latter with respect to the discs, means lying in the path of the needle arm to locate it on the margin of a disc, means to positively move the arm across the disc toward the disc-center, 55 during the reproduction period, and means cooperating with the operating means and influenced by the needle arm when reaching the inner end of a record groove for lifting the said needle arm, the said means for moving 60 the arm inwardly also being adapted to move 65 the arm outwardly beyond the periphery of the disc.
12. A sound reproducing machine including a series of record discs rotatable upon a common axis, a sound box and needle arm, a support to carry the latter movable in a line paralleling the said axis, means to impart movement to the support, means to terminate such movement at a given position whereby the needle arm will lie at substantially the 70 reproducing position at a given disc, means to automatically locate the needle arm above a disc-margin, means to raise and lower the needle arm with respect to the surface of the disc, and means by which to carry the arm 75 positively toward the disc-center and to carry it positively outward from said disc-center.
13. The combination in a sound reproducing machine including a record disc, a sound box and needle arm mounted and adapted to swing in a plane paralleling the plane of the disc, of means carrying the sound box adapted to move the same in a line parallel to the axis of disc rotation, and means lying in the 80 path of a part of the sound box adapted, when met by the latter in its travel, to engage 85 and cause the same to swing toward the disc-center but arranged to cause the needle arm to take up a position at the margin of the disc.
14. In a sound reproducing machine, the combination with a member having a record groove therein, a sound box, and a stylus adapted to approach the record groove in a direction at right angles to the surface with which said stylus is to have contact, and a member having an inclined surface adapted to be placed in adjusted positions in the path 90 of a part of the sound box adapted to guide the stylus into the starting end of the record groove.
15. In a sound reproducing machine, the combination with a record disc, and a sound box and needle arm adapted for movement in a direction at right angles to the plane of said disc, of means lying in the path of an extension of said sound box in one direction of its movement having a downwardly inclined surface to receive said extension terminating in an open channel-member, and adapted to be disposed with respect to the disc whereby 100 the extension in passing through said channel-member will locate the needle arm at the starting end of the groove of said record disc.
16. In a sound reproducing machine, the combination with a record disc, and a sound box and needle arm adapted for movement in a direction at right angles to the plane of said disc, of means lying in the path of an extension of said sound box in one direction of its movement having a downwardly inclined surface to receive said extension terminating in an open channel-member, and adapted to be disposed with respect to the disc whereby 110 the extension in passing through said channel-member will locate the needle arm at the starting end of the groove of said record disc.
- 120 16. In a sound reproducing machine, the combination with a record disc, and a sound box and needle arm adapted for movement in a direction at right angles to the plane of said disc, of means lying in the path of an extension of said sound box in one direction of its movement having a downwardly inclined surface to receive said extension terminating in an open channel-member, and adapted to be disposed with respect to the disc whereby 115 the extension in passing through said channel-member will locate the needle arm at the starting end of the groove of said record disc.
- 125 17. In a sound reproducing machine, the combination with a record disc, and a sound box and needle arm adapted for movement in a direction at right angles to the plane of said disc, of means lying in the path of an extension of said sound box in one direction of its movement having a downwardly inclined surface to receive said extension terminating in an open channel-member, and adapted to be disposed with respect to the disc whereby 130 the extension in passing through said channel-member will locate the needle arm at the starting end of the groove of said record disc.

said channel-member will locate the needle arm at the starting end of the groove of said disc, and means adapted for manual operation connected with the said extension adapted to abut the edge of the record disc for locating said channel member.

17. The combination in a sound reproducing machine including a record disc, a sound box and needle arm adapted to swing parallel to the plane of the disc, of means to carry and move said arm in a line parallel to the axis of disc rotation, and means adjustable with respect to the path of movement last described and having an inclined surface to receive an extension of the sound box and terminating in a channel to receive into it said extension and out of which the latter is adapted to pass.

18. The combination in a sound reproducing machine, including a record disc, a sound box and needle arm, of means to carry and move the said sound box and needle arm in a line parallel to the axis of disc rotation, means lying in the path of an extension of the sound box having a downwardly inclined surface to receive the same and terminating in an open channel member to receive said extension through and out of which it is adapted to pass, and means to adjust said means.

19. A sound reproducing machine including in combination with a shaft and a series of record discs thereon, a sound box and needle arm, a vertically movable support for said sound box, said sound box and needle arm being adapted to swing in two planes lying at right angles to one another, a line of teeth on the support arranged longitudinally thereof in spaced series, a constantly rotating pinion normally in one of the spaces between two adjacent spaced series of the teeth, driving mechanism, a latch to fix the support with respect to one of the discs, means influenced by the needle arm when and as it reaches the limit of its travel toward the center of a disc, and having engagement with the sound box, adapted to swing the needle arm toward and outside the disc margin, and means cooperating with the driving mechanism adapted for operating the latch to release the support permitting it to carry one of the series of teeth into engagement with the pinion, said latch being adapted to reengage and fix the support in position when and as a succeeding space between the spaced series of teeth arrives opposite said pinion.

20. A sound reproducing machine including, in combination, the body of the machine, a support guided vertically therein, a sound box and its needle arm mounted on said support, a series of teeth carried by the support disposed in a line extending laterally of the same, teeth disposed in a line extending longitudinally of the support, power mechanism mounted in the body including a pinion adapted to engage the teeth but normally dis-

engaged therefrom, a latch engaging the support to fix it with respect to the body, means influenced by the needle arm to withdraw the latch through the instrumentality of said power mechanism to release the support and permit the laterally disposed teeth to move into engagement with the said pinion, the latter through said power mechanism being thereby moved into engagement with the longitudinally disposed line of teeth for elevating the support therethrough, a member for maintaining engagement of the pinion and the last named teeth during the elevating action, a stud movable with the support to shift the member, and means to disengage the pinion from the teeth.

21. A sound reproducing machine including in combination with a series of spaced rotatable record discs, a support arranged for movement in a line parallel with the axis of disc rotation, a sound box and needle arm mounted on said support, driving means in constant operation adapted to be engaged with the support for moving it but normally disengaged therefrom, a latch to fix the support in a given position, gearing in mesh with said means influenced by the needle arm at the end of its travel toward the disc-center adapted to lift the said needle arm, means to swing the arm away from the disc-center, and means to retract the latch to permit the support to engage said driving means.

22. A sound reproducing machine including, in combination, a support, a mounting therefor in which it is adapted to shift in opposite directions, said support having opposing lines of teeth extending longitudinally thereof facing one another and also having teeth extending laterally thereof at one end of and disposed between the said opposing lines of teeth, constantly operating mechanism including a swingable shaft and a pinion disposed between the opposite lines of teeth adapted to be engaged with either series thereof but normally disengaged therefrom, a swingable plate carrying the shaft, a latch to fix the support in a given position in one of its directions of travel, and a member to automatically engage behind the plate for holding the pinion in engagement with one of the said series of teeth when said pinion is moved into such engagement.

23. A sound reproducing machine including, in combination, a support capable of shifting in opposite directions, a mounting in which the same is guided, said support having opposing lines of teeth extending longitudinally thereof facing one another and also having teeth extending laterally thereof at one end of and disposed between the said opposing lines of teeth, constantly operating mechanism including a swingable shaft and a pinion thereon disposed between the opposite lines of teeth adapted to be engaged with one of said series but normally disengaged

therefrom, a swingable support for the shaft, a latch to fix the support in a given position, a member to automatically engage behind the plate for holding the pinion in engagement with one of the said series when said pinion is moved to such engagement, a spring constantly urging the plate in a direction to disengage the pinion, and a stud on the support to engage and move the member to release the plate during the travel of the support in one direction.

24. A sound reproducing machine including, in combination, a series of record discs, a movable support guided in a line parallel to the axis of disc rotation, a sound box and needle arm mounted on the support, a series of teeth extending along the support arranged in a line parallel to the line of travel thereof, a pinion for engaging the teeth, driving mechanism therefor, gearing operatively engaging the needle arm to swing the same and influenced by said arm, a worm rotatable with the pinion with which said gearing is engageable, a second gearing operated by said driving mechanism, means engageable with a part of the second gearing and with the sound box adapted to tilt the latter and lift the needle arm and also adapted to disengage the worm from the first named gearing, a latch to fix the support in a given position in its line of travel, and a lever operated by the said second gearing to retract the latch for releasing the support carrying the teeth thereof upon the pinion.

25. A sound reproducing machine including in combination with the machine body, a support guided therein adapted to travel in opposite directions in a direct line, a sound box and needle arm mounted thereon, and automatically operated mechanism adapted to be brought into operative engagement with the same for separately imparting an unrelmitting movement automatically and positively to such support in one direction, and for imparting an intermittent movement thereto in an opposite direction.

26. A sound reproducing machine including in its construction, in combination with a series of spaced rotatable record discs, a support capable of moving in a line parallel to the axis of rotation of the discs, means for guiding the support in its movement, a sound box and needle arm carried by the support, operating mechanism to adjust the support for locating the needle arm opposite a disc, means operatively connected to the needle arm capable of moving the latter across the disc in either direction, and means both for lifting the needle of the arm out of the record groove and for permitting it to enter the same.

27. A sound reproducing machine including in combination a sound box, a traveling support carrying the same, two series of gear teeth on the support in opposed positions, a

shaft extending between the two series of teeth and a pivotally mounted bearing for the same, a pinion on said shaft to engage either series of teeth, gearing to rotate said shaft, and means operated by the gearing to automatically swing the shaft to move its pinion laterally through the space between said two series of teeth.

28. A sound reproducing machine including in combination a sound box, a support for the same, guide means in which the support is adapted to travel in opposite directions, two series of teeth on the support in opposed positions, a shaft extending between the two series of teeth, a pinion thereon, said shaft being mounted to swing whereby the pinion may mesh with either series of teeth, gearing to drive the shaft, and means operated by the gearing to automatically swing the shaft to move the pinion away from the line of one series of teeth, said pinion being free to be engaged with the other of the series of teeth.

29. A sound reproducing mechanism including a main frame, a sound box, a support for the latter adapted to move by gravity in one direction, means mounted on the frame to guide the support, two sets of opposed gear teeth on the support, one of said series being divided into spaced groups, a shaft mounted to swing between the parallel lines of the teeth, a pinion thereon, means for maintaining said pinion in position for engaging any one of the said groups of teeth, gearing for imparting a continuous drive to the shaft, a latch on the main frame in control of the support for positioning the spaced groups of teeth clear of the pinion, and means operated by said gearing to actuate the latch and permit the support to move to permit one of said groups of teeth to engage said pinion.

30. A sound reproducing machine including in its construction a frame, a support guided therein adapted to move in two opposite directions, a sound box mounted on the support, said support having an inverted U-shaped opening therein, gear teeth arranged therein in two opposed lines, a shaft extending between the two lines of teeth and mounted to swing laterally, a pinion mounted on the shaft, power gearing driving the shaft and pinion continuously in one direction, and means to normally hold the shaft with its pinion in position to mesh with one of the series of teeth, said support in one direction of its travel being supported on the rotating pinion and being moved in the other direction by said pinion.

31. A sound reproducing machine including in its construction a frame, a support thereon adapted for a reciprocating movement with respect thereto, a series of teeth on the support arranged in the form of a U, a shaft mounted to swing between the two lines

of teeth, a pinion thereon to engage the said teeth, and gearing to rotate the shaft and pinion, the said support in one direction of its travel being supported on the rotating pinion, and positively moved in the other direction of its travel by the same, said pinion moving from one of the parallel lines of teeth to the other by its engagement, during rotation, with the teeth intermediate the said 10 parallel lines of teeth.

32. A sound reproducing machine including in its construction a frame, a support guided thereon in a vertical line having a series of spaced groups of teeth arranged in

a parallel line to the line of travel of said support, a shaft mounted on the frame including a pinion stationed in position to engage the said teeth, a latch for fixing the support at any one of several elevations whereby the pinion will lie in a space between adjacent groups of the teeth, gearing to drive the shaft and its pinion, and means operated by the gearing to disengage the latch for releasing the support permitting the teeth of the latter to descend upon said pinion. 15 20 25

In testimony whereof I affix my signature.

WILLIAM E. BIRKET.
